CLAIM

The ornamental design for a belt with securing hooks for attachment to collection bag for kidney and bladder liquids, as shown and described.

DESCRIPTION

FIG. 1 is a top front perspective of a belt with securing hooks for attachment to collection bag for kidney and bladder liquids, showing my design;

FIG. 2 is a front elevation view thereof;

FIG. 3 is a bottom plan view thereof; and,

FIG. 4 is a rear elevation view thereof.

The broken line showing of the collection bags for kidney and bladder liquids in FIG. 1 is included for the purpose of illustrating environmental structure and forms no part of the claimed design.
